G. R. BIRNEY.
SURFACE HEATER.
APPLICATION FILED MAR. 15, 1912.

1,135,493.

Patented Apr. 13, 1915.

UNITED STATES PATENT OFFICE.

GEORGE R. BIRNEY, OF PHILADELPHIA, PENNSYLVANIA, ASSIGNOR TO THE BARBER-
ASPHALT PAVING COMPANY, OF PHILADELPHIA, PENNSYLVANIA, A CORPORA-
TION OF WEST VIRGINIA.

SURFACE-HEATER.

1,135,493.

Specification of Letters Patent. Patented Apr. 13, 1915.

Application filed March 15, 1912. Serial No. 683,974.

To all whom it may concern:

Be it known that I, GEORGE R. BIRNEY, of the city and county of Philadelphia, State of Pennsylvania, have invented certain new and useful Improvements in Surface-Heaters, of which the following is a specification, reference being had to the accompanying drawings.

My invention relates to a surface heating machine of the general character shown in United States Letters Patent No. 931,085, granted August 17th, 1909 to Prescott and Kerns. Said machine consists essentially in the combination of a steam roller, with a transverse down draft flue terminating in a hood by means of which the heated products of combustion produced in the fire box of the steam boiler by which the steam roller is propelled, may, as desired, be deflected and caused to impinge upon the surface to be heated. Such surface heaters are used for the purpose of heating bituminous paving surfaces and all other kinds of surfaces for various purposes. In a heater of this character it is customary to employ a blast or other similar means for the purpose of inducing the required draft to deflect the heated products of combustion downwardly to the surface to be heated, and in the Prescott and Kerns patent referred to, this steam blast is obtained by means of a pipe carrying steam from the steam boiler of the engine, and discharging it within the flue. In a heater of this character it is very desirable to heat the surface to the highest possible temperature in the shortest possible time. The steam blast by blowing up the fire tends to facilitate this, but to a certain extent this is interfered with by the comparatively low temperature of the steam, which mingling with the heated products of combustion tends to somewhat reduce their temperature and by the fact that the steam pipe being exposed to the atmosphere, the steam will condense thereby reducing the pressure of the blast and wetting the surface that is to be heated. My invention relates to means for obviating this difficulty, and markedly increasing the heat which is procurable in a short time beneath the hood of the machine. I accomplish this by causing the pipe which conducts the steam for the blast from the boiler to pass within the flue for a considerable portion of its length, whereby the steam is not only prevented

from cooling but also superheated and delivered at the blast at a much higher temperature and approximately equal to that of the gas, thereby preventing condensation. My invention also relates to a modified construction of the fire box of the steam boiler, whereby the heated products of combustion may be discharged more directly and at a higher temperature into the flue by which they are carried to the surface to be heated. 60

In the accompanying drawings, I have illustrated a surface heater embodying my invention.

Figure I, shows the machine partly in elevation and partly in longitudinal section. 70 Fig. II, is an enlarged sectional view of the fire box and adjacent parts of the boiler.

The parts of the machine which are common to steam rollers of this type need not be especially referred to, as they are well 75 known.

The steam boiler 1, has its fire box prolonged in the form of an extension 2, with corresponding prolongation of the grate bars 3. The sides of this extension, as well as the sides of the remainder of the fire box are water jacketed and at the top of the extension are short fire tubes 5, 5, passing through that portion of the boiler (of comparatively slight height) which overlies the extension 80 of the fire box. This latter portion of the boiler is surmounted by the curved conducting piece 7, by which the products of combustion, passing through the short fire tubes 5, are led to the horizontal flue 10. This flue is of considerable length and projects beyond the end of the steam roller, the projecting end being supported by the braces 11, 11. At its farthest extremity the horizontal flue 10, communicates with the vertical flue 90 12, on the lower end of which is secured a hood 13, with capacity for vertical adjustment with relation to the flue, so that it may be lowered to the surface to be heated, or raised sufficiently thereabove. For the purpose of controlling the motion of the hood, a steam cylinder 15, surmounts the vertical flue 12, and by means of connections not shown, effects the operation of the hood. A steam pipe 20, leads from the steam boiler 100 and enters the horizontal flue in proximity to the end of the flue nearest the boiler. The pipe passes through nearly the entire length of this horizontal flue and then after emerging has inserted within it a valve 30, which 105

may be operated by means of the rod 31, and handle 32. By means of this valve steam passing through the steam pipe may be sent to the cylinder 15, which operates the hood, or to the steam blower 35, which is of known construction, and is mounted centrally within the vertical portion of the flue and is useful to accelerate the down draft by which the heated products of combustion are led from the fire box to the surface to be heated, whereby the draft is so increased as to blow up the fire and secure the required temperature.

It will be noted that the heated products of combustion are, by the arrangement which I have shown, led directly from the fire box, through the short fire tubes 5, and conducting piece 7, into the flue, whereas in previous constructions of this character, they have been taken from the side of the boiler. It will also be noted that the steam by which the blast is produced is highly superheated because of the length of the steam pipe traversing the flue, wherein the steam is subject to very high temperature, so that when discharged at the blast, it does not substantially differ in temperature from the products of combustion traversing the flue, thus markedly raising the temperature at which these products of combustion are caused to impinge upon the surface to be heated.

By means of an apparatus of this character, I am enabled to obtain a temperature of one thousand degrees or more underneath the hood very rapidly, and can thus sufficiently heat the surface of an asphalt pavement, so that in two or three minutes the entire surface may be removed and new surface material put in its place.

Having thus described my invention, I claim:

1. In a machine for heating surfaces, the

Copies of this patent may be obtained for five cents each, by addressing the "Commissioner of Patents, Washington, D. C."

combination of a vehicle; means mounted thereon for producing heated products of combustion; a long horizontal flue, with a depending end fitted with a hood, whereby these heated products of combustion are led to and caused to impinge upon the surface to be heated; a steam blast apparatus discharging within said flue, near the hood, and inducing the required down draft within the flue; a steam pipe leading from a boiler to said blast, said steam pipe being arranged to pass for a considerable distance within the flue, whereby the high temperature of the steam is maintained and condensation thereof prevented. 45 50 55

2. In a machine for heating surfaces, the combination of a vehicle; means mounted thereon for producing heated products of combustion; a long horizontal flue, with a depending end fitted with a hood, whereby these heated products of combustion are led to and caused to impinge upon the surface to be heated; a steam blast apparatus discharging within said flue, near the hood, and inducing the required down draft within the flue; a steam pipe leading from a boiler to said blast, said steam pipe being arranged to pass for a considerable distance within the flue, whereby the high temperature of the steam is maintained and condensation thereof prevented, said steam pipe being caused to emerge from the flue for a sufficient distance before reaching the steam 60 65 70 75 blast apparatus for purposes of regulation.

In testimony whereof, I have hereunto signed my name at Philadelphia, Pennsylvania, this eleventh day of March, 1912.

GEORGE R. BIRNEY.
